H. D. CHURCH.
HYDROCARBON MOTOR.
APPLICATION FILED NOV. 10, 1917.

1,382,954.

Patented June 28, 1921.

UNITED STATES PATENT OFFICE.

HAROLD D. CHURCH, OF DETROIT, MICHIGAN, ASSIGNOR TO PACKARD MOTOR CAR COMPANY, OF DETROIT, MICHIGAN, A CORPORATION OF MICHIGAN.

HYDROCARBON-MOTOR.

1,382,954.

Specification of Letters Patent. Patented June 28, 1921.

Application filed November 10, 1917. Serial No. 201,294.

To all whom it may concern:

Be it known that I, HAROLD D. CHURCH, a citizen of the United States, and resident of Detroit, Wayne county, State of Michigan, have invented certain new and useful Improvements in Hydrocarbon-Motors, of which the following is a specification.

This invention relates to hydrocarbon motors and particularly to the throttle, the 10 governor, and the connections therebetween.

One of the objects of the invention is to simplify the construction of the connecting means between the governor and the throttle valve of a hydrocarbon motor.

Another object of the invention is to provide connecting means between the governor and throttle valve of a hydrocarbon motor that will withstand extremely hard usage.

Another object of the invention is to provide a novel arrangement of spring means for the governor of a hydrocarbon motor.

Another object of the invention is to provide connecting devices which may be used between the governor and throttle valve of a hydrocarbon motor, with a novel arrangement of lubricating means.

Other objects of the invention will appear from the following description taken in connection with the drawings which form a 30 part of this specification, and in which:

Figure 1 is a side elevation and part sectional view of a hydrocarbon motor embodying the invention;

Fig. 2 is an enlarged vertical sectional view through part of the connecting means between the governor and throttle valve of the motor shown in Fig. 1;

Fig. 3 is a transverse vertical section substantially on the line 3—3 of Fig. 2; and

Fig. 4 is a detail perspective view of the governor rod button.

Referring to the drawings, 10 represents the crank case or supporting base of a hydrocarbon motor, and 11 is a cylinder block mounted thereon. 12 indicates the motor carbureter which is connected to the intake manifold 13 by an intake pipe 14. In the intake pipe is a throttle valve 15 which is actuated by an arm 16 in a casing 17 secured to the intake pipe 14. An adjustable stop 18 cooperates with a lug 19 on the arm 16 to determine the closed position of the throttle. In other words, the closed position of the throttle is its idling position wherein a small amount of mixture is permitted to

pass the throttle to permit the motor to run very slowly.

Suitably supported upon the motor crank case 10 is a casing in which is a governor 21 operated by a shaft 22 and a gear 23 thereon. 60 It will be understood that the gear 23 is connected to be driven by one of the motor gears such as the cam shaft gear, not shown.

The shaft 22 is shown as of hollow construction and it extends through and operates the impeller of a water pump 24 which is also mounted on the crank case 10. Thus the extended end of the shaft 22 is shown at 22 in Figs. 1 and 2, this part of the shaft 65 projecting through the pump 24. 70

The governor 21, above referred to, is keyed to the end of the shaft 22 and secured thereon as by a nut 25, and the arms 21^a of the governor are pivoted at 26 and have their operating ends 27 in contact with the head 28 of an operating rod 29, which extends entirely through the driving shaft 22. The part of the rod 29 passing through the shaft 22 is indicated in dotted lines in Fig. 1, and the end of the rod which projects 75 from the part 22^a of the shaft 22 is indicated at 29^a, being in the form of a button having a flat transverse surface or face 30, as shown particularly in Figs. 2 and 4. Also in Fig. 2 it will be seen that the button 29^a is formed 80 as a separate element from the rod 29 and is threaded into the latter. Also the rod 29 has a bearing 31 in the end 22^a of the shaft 22 so that it will be retained in a concentric position relative to the shaft and may be 85 moved endwise therein. A similar bearing may be provided at the other end of the driving shaft 22. From the above it will be understood that upon the rotation of the shaft 22 by means of the gear 23 the arms 90 21^a of the governor will swing outwardly by centrifugal force and the ends 27 will thereby push the rod 29 toward the right in Fig. 1. It will be seen also that the mechanism thus far described contains no spring 95 for returning the governor to its inoperative position, as shown in Fig. 1.

A connecting device between the governor and the throttle valve, above referred to, as well as a spring for yieldingly holding the 105 governor in its inoperative position and the throttle valve in its open position, are supported on the crank case 10 in a support or casing 32. The principal parts of this connecting device are a rock shaft 33 which is 110

connected to the throttle arm 16 as by an arm 34, a link 35, and a bearing support 36 which is shown as supported by and immediately beneath the rock shaft. The rock 5 shaft and bearing support are housed within the casing 32, and the connecting rod 35 above referred to is shown as housed within a tube 37 which extends from the casing 32 to the casing 17 for the throttle arm 16. 10 Thus all of the connections between the governor and throttle valve are suitably housed to protect them from dirt and from being tampered with.

The bearing support 36 is carried by the 15 rock shaft 33 on a pair of arms 38 which are keyed to the rock shaft as shown in Fig. 3, and the connection between the arms 38 and the support 36 is a pivotal one as shown at 39, particularly in Figs. 1 and 2. Thus it 20 will be seen that the swinging movements of the arms 38 with the rock shaft 33 are also conveyed to the support 36 except that the latter may be retained in a vertical position by swinging on its pivots 39.

25 The support 36 is shown as of hollow construction and carries within it a thrust bearing 40 which comprises a series of balls 41, a disk 42 having an outer flat face 43 adapted to coöperate with the flat face 30 of the 30 button 29^a hereinabove described, and a ring 44 having an outer spherical face 45 adapted to coöperate with a ring 46 retained in the support by a cap 47 threaded therein and locked by a wire 48. The cap 47 is formed 35 with a central boss 49 and a spring 50 surrounds the boss and bears against the cap to yieldingly press the support 36 toward the left in Figs. 1 and 2. The other end of the spring 50 bears against the inner end of a 40 sleeve 51 which is threaded into the casing 32, as shown particularly in Fig. 1, thus providing an adjustment for the spring 50. The sleeve 51 may be locked in adjusted position by a nut 52.

45 From the above description it will be seen that the support 36 is arranged directly between the rod 29 and the spring 50 and the longitudinal axes of the rod and the spring, as well as of the bearing 40, are substantially 50 in line. Of course the swinging movement of the support 36 will carry the center of the bearing 40 slightly out of line with the axis of the rod 29, but this will be taken care of by the flexibility of the spring 50 and a 55 slight relative movement between the flat ground surfaces 30 and 43 of the button 29^a and disk 42 respectively. Also, any slight angularity will be taken care of by the automatic adjustment of the ring 44 in the ring 60 46 by reason of the spherical surfaces thereof.

65 It will be noted that the rotating driving shaft 22 has its end 22^a extending into the casing 32 through an opening 53 which is slightly larger than the shaft so that abso-

lutely correct alinement of these parts is not necessary. The support 36 also is provided with an opening 54 somewhat larger than the button 29^a so that the latter may enter the support and need not be accurately 70 alined with the center thereof. This construction of parts greatly facilitates manufacture and permits of much more simple construction in the connection between the support 36 and its carrier. 75

The spring 50, above referred to, is of course under compression and through the bearing support 36 and the bearing therein it yieldingly presses the rod 29 toward the left in Figs. 1 and 2, thus holding the governor 80 in its inoperative position. When the governor operates the rod 29 is moved endwise against the action of the spring 50. By reason of the fact that the spring 50 is mounted in a stationary part of the casing it is readily 85 adjustable while the motor is running. The spring also acts through the support 36, rock shaft 33 and the connections to the throttle arm 16 to yieldingly retain the throttle valve in its open position, the valve being 90 closed or partly so by the action of the governor, as will be understood from the above description.

Means are provided for lubricating the 95 entire connecting device within the casing 32 by a single oil feeding means. The rock shaft 33 is drilled out so that it is hollow, as shown in Figs. 2 and 3, and an oil feeding cup 55 is connected to the shaft through a channel 56 and a transverse hole 57 in the 100 rock shaft. From the oil thus fed to the interior of the rock shaft the bearings 58 and 59 for the rock shaft are lubricated through the opening 57 which leads to a groove 60 formed in the rock shaft adjacent the bearing 58 and a hole 61 which leads to the bearing 59. 105

Means are provided for carrying oil from the interior of the rock shaft to the support 36 in the form of a pipe 62 which extends downwardly from the rock shaft to a point directly over the support 36. The top of the support is in the form of a cup 63 directly under the end of the tube 62 and an opening 64 permits the oil received by 110 the cup to pass to the interior of the support 36 and therefore to the bearing 40. Thus the hollow support 36 may be filled up to a level with the bottom of the opening 54 before overflowing. Also a small 115 amount of oil will be carried along the button 29^a and the end of the shaft 29 to the bearing 31, this bearing requiring a very small amount of lubricant since the rod 29 does not necessarily turn in it but only slides 120 endwise in it as the governor operates. 125

It will be observed that the opening through the pipe 62 is somewhat smaller than the inlet channel 56 from the feeding cup 55 so that the hollow rock shaft 33 will 130

act as a sort of measuring device for feeding oil to the entire mechanism. Thus oil may be fed to the rock shaft through the channel 56 faster than it will run out through the tube 62. Oil may be put into the cup 55 until it appears to be full and this will give sufficient lubrication to the bearings 58 and 59 and the oil will then run out of the rock shaft through the tube 62 and into the cup 63 and hollow support 36 until the latter is filled. By oiling the device in this manner at regular intervals all of the parts will receive approximately the right amount of lubrication.

15 It will be seen further that the outlet end of the tube 62 will be over the cup 63 regardless of the position of the latter, as the tube will turn with the rock shaft as the latter is rocked by the shifting of the support 36 due to the action of the governor.

20 It will be understood further that my invention is not limited to the details of construction shown and other forms may be used without departing from the spirit or 25 scope of the invention.

Having thus described my invention, what I claim and desire to secure by Letters Patent is:—

1. In a hydrocarbon motor, the combination 30 with a throttle valve therefor, a centrifugal governor of a hollow shaft for driving said governor, a rod extending through said shaft and operated by said governor, a spring adapted to exert pressure against the said 35 rod for yieldingly holding the governor inoperative and the throttle open, a member interposed between said rod and said spring capable of lateral movement with respect to said rod and means pivotally connecting said 40 throttle valve and said member.

2. In a hydrocarbon motor, the combination 45 with a throttle valve therefor and a centrifugal governor, of a hollow shaft for driving said governor, a rod extending through said shaft and operated by said governor, a swinging arm connected to said 50 throttle valve and adapted to be operated by said rod, a bearing member carried by said arm engaging the free end of said rod and capable of lateral movement with respect thereto, and a spring acting against said member to yieldingly hold the governor inoperative.

3. The combination with the throttle valve 55 of a hydrocarbon motor, of a governor, a rock shaft arranged between the governor and the valve, connections from said shaft to the valve, a device entirely supported by said rock shaft, a rod extending from the 60 governor to said device, and a spring acting directly against said device to press the governor to inoperative position.

4. In a hydrocarbon motor, in combination, a throttle valve, a governor, a connecting device between the throttle valve and

governor comprising a rock shaft having an arm, a bearing support on said arm, a bearing in said support and means for feeding oil to said rock shaft and from said rock shaft to said support and bearing.

5. In a hydrocarbon motor, in combination, a throttle valve, a governor, a connecting device between the throttle valve and governor comprising a hollow rock shaft having an arm, a hollow bearing support on 75 said arm, a bearing in said support and means for feeding oil to said rock shaft and from said rock shaft to said support and bearing.

6. In a hydrocarbon motor, in combination, a throttle valve, a governor, a connecting device between the throttle valve and governor comprising a rock shaft, bearings for said shaft, a bearing support carried by 80 said rock shaft, a bearing in said support and 85 means for feeding oil to the bearings of said rock shaft and through the rock shaft to said support.

7. In a hydrocarbon motor, in combination, a throttle valve, a governor, a connecting device between the throttle valve and governor comprising a rock shaft, a bearing support carried by said rock shaft and having a cup on the upper surface thereof, 90 said rock shaft having a spout leading to a 95 point over said cup, a bearing in said support and means for feeding oil to said shaft and through said spout and cup to said support and its bearing.

8. In a hydrocarbon motor, in combination, a throttle valve, a governor, and connections from the governor to the valve comprising a casing, a rock shaft in the casing having connections running to the valve, a rod from the governor extending into said casing, a hollow bearing support carried by said rock shaft, a bearing in said support coöperating with said rod, a spring coöperating with said support, and means for feeding oil to said support through said rock shaft.

9. In a hydrocarbon motor, in combination, a throttle valve, a governor, and connections from the governor to the valve comprising a casing, a rock shaft in the casing having connections running to the valve, a rod from the governor extending into said casing, a hollow bearing support carried by said rock shaft, a bearing in said support coöperating with said rod, a spring coöperating with said support, and means for feeding oil to the rock shaft and through the latter to said support and its bearing.

10. In a hydrocarbon motor, in combination, a throttle valve, a governor, a governor shaft, and connections from the governor to the valve comprising a rock shaft having connections to the valve, a bearing support adapted to swing with said rock shaft, a bearing in said support, a rod operated by the governor and movable axially, the end 125

of said rod extending beyond the governor shaft and slidingly engaging said bearing to permit slight lateral relative movement as the bearing support swings in response to the action of the rod, and a spring acting yieldingly against the other side of said bearing support.

11. In a hydrocarbon motor, in combination, a throttle valve, a governor, and connections from the governor to the valve comprising a rock shaft having connections to the valve, a bearing support adapted to swing with said rock shaft, a bearing in said support, movable with respect thereto, a rod operated by the governor and movable axially, the end of said rod slidingly engaging said bearing to permit slight lateral relative movement as the bearing support swings in response to the action of the rod, and a

spring acting yieldingly on said governor 20 through said bearing and said rod.

12. In a hydrocarbon motor, in combination, a throttle valve, a governor, and connections from the governor to the valve comprising a rock shaft having connections to the valve, a bearing support pivotally carried by said rock shaft and adapted to swing with said rock shaft, a thrust bearing mounted in and engaging said support, an endwise movable rod operated by the governor 30 and having its end slidingly engaging said bearing to permit slight variation in axial alignment of rod and bearing as the rock shaft swings, and a spring acting yieldingly to hold the rock shaft against swinging. 35

In testimony whereof I affix my signature.

HAROLD D. CHURCH.
